UNITED STATES PATENT OFFICE

FRED B. KING, OF ALBION, MICHIGAN, ASSIGNOR TO NATIONAL SPRING AND WIRE COMPANY, OF ALBION, MICHIGAN, A CORPORATION OF MICHIGAN.

SPRING-SEAT CONSTRUCTION.

986,723.

Specification of Letters Patent. Patented Mar. 14, 1911.

Application filed November 14, 1910. Serial No. 592,194.

To all whom it may concern:

Be it known that I, FRED B. KING, a citizen of the United States of America, residing at Albion, in the county of Calhoun and 5 State of Michigan, have invented certain new and useful Improvements in Spring-Seat Construction, of which the following is a specification, reference being had therein to the accompanying drawings.

10 In spring construction of seats adapted for vehicles, it is desirable that the parts be so disposed as to be quickly assembled and that the seat structure when completed be adapted to use for either light or heavy 15 loads.

This invention relates to seat construction provided with means whereby the main springs may be reinforced if desired by auxiliary springs which aid in taking up the 20 load after the main springs have been partially depressed, the auxiliary springs being so arranged as to constitute a bodily removable unit which may be easily placed in position in the main seat when desired.

25 The invention consists in the matters hereinafter set forth, and more particularly pointed out in the appended claims.

In the drawings, Figure 1 is a plan view, 30 in section, of an assembled seat that embodies features of the invention; Fig. 2 is a view in end elevation thereof; Fig. 3 is a view in section on or about line $x-x$ of Fig. 1, and Fig. 4 is a view in perspective of a portion of the seat.

35 As herein indicated as a preferred form of construction a marginal base frame is made of a wire 1 of proper proportions along the sides and ends of which a series of regularly disposed spiral coil marginal main 40 springs 2 of the usual "furniture" type or "hour glass" pattern are secured at intervals as by clips 3 or like suitable means. The lower convolutions of inner main springs 4 of like pattern are mounted on 45 spacing rods 5 secured near their ends in pairs in parallel relation to the lower convolutions of the marginal springs 2 which are secured to the ends of the base frame, the ends of the rods being unattached to and 50 clear of the base frame. The inner portions of the lower convolutions of the main springs on the sides of the main frame are likewise connected by suitable clips 6 to side bars 7 similar in all respects to the spacing rods 5. The upper convolutions of the mar-

ginal springs 2 are secured together by an upper rim frame 8 which is fastened in position by clips 9 preferably of the same type as those used in the base frame. The upper convolutions of the interior springs 4 are 60 not stayed.

An auxiliary base frame is formed of intersecting strips 10, preferably of flat spring sheet material which are spaced to lie between the main frames, are riveted or otherwise secured together at their intersections and are detachably secured to the lower rim frame 8 as by folding the ends around the wire forming the latter. At each intersection an auxiliary spring is mounted on the 65 strips. The latter which are preferably co-noidal as indicated at 11, are each secured to the strips by insertion through tongues or loops 12 struck out from the bodies of the strips or may be otherwise made fast in any 70 suitable manner. Their upper extremities are interconnected by resilient and flexible bars 13 which are free from connection with either the main base frame or the upper rim frame or from the main springs. Furthermore, the auxiliary frame strips 10 when placed on the main frame, lie above the rods 75 and side members 5.

As a result of this construction a spring seat is obtained which, while it is available 85 for use in supporting heavy loads, may also be arranged to carry lighter burdens by removing the auxiliary springs, which is readily done by disconnecting the auxiliary frame strip ends from the lower rim frame. 90

In the use of the complete assembled structure a load on the central portion of the main springs, as it partially depresses the latter, forces the spacing rods down into approximately the positions indicated in Fig. 95 3, clear of the auxiliary base frame which is not effected until further depression of the main springs brings the load to act on the shorter auxiliary springs. The auxiliary frame then takes up its share of weight and 100 transmits it to the lower rim frame which is of course usually rigidly supported. This produces a cheap and efficient seat which is noiseless in its action and which may be adjusted for either light or heavy service without difficulty as the auxiliary members may be removed if desired, without disintegrating the main structure.

Obviously, changes in the details of construction may be made without departing 110

from the spirit of the invention and I do not care to limit myself to any particular form or arrangement of parts.

I claim as my invention:—

5. 1. In spring constructions, a marginal base frame, spiral marginal main springs secured at intervals on the sides and ends of the base frame, spacing rods supported solely by the end marginal springs, spiral inner main springs each independently supported by the spacing rods, and an upper rim frame connecting the side and end marginal main springs.
10. 2. In spring constructions, a marginal base frame, spiral marginal main springs secured at intervals on the sides and ends of the base frame, said bars connecting the lower portions of the side marginal springs independently of the base frame, spacing rods supported by the lower portions of the end marginal main springs independently of the base frame, spiral inner main springs each independently supported on the spacing rods and an upper rim frame to which the upper portion of the side and end marginal main frames are connected.
15. 3. In spring constructions, a marginal base frame, spiral marginal main springs secured at regular intervals by their base convolutions to the sides and ends of the base frame, spacing rods secured to and supported by the base convolutions of the end marginal main springs independently of the base frame, inner spiral main springs whose lower convolutions are secured to and supported by the spacing rods independently of each other and of the base frame and an upper rim frame secured to and supported by the upper convolutions of the end and side marginal main springs only.
20. 4. In spring constructions, a marginal base frame, spiral marginal main springs secured at regular intervals by their base convolutions to the sides and ends of the base frame, spacing rods secured to and supported by the base convolutions of the end marginal springs independently of the base frame, spacing bars secured to and supported by the base convolutions of the side marginal main springs independently of the base frame, spacing rods, spiral inner main springs secured at regular intervals by their base convolutions to the spacing rods independently of the marginal base frame, and an upper rim frame connected to and supported solely by the upper convolutions of the marginal end and side main springs.
25. 5. In spring constructions, a marginal base frame, spiral marginal main springs secured at regular intervals on the sides and ends of the base frame, spacing rods secured to and supported by the marginal end main springs independently of the marginal base frame, spiral inner main springs secured at regular intervals on the spacing rods, an

upper rim frame secured on the upper portions of the side and end main springs, an auxiliary base frame secured to the marginal base frame over the spacing rods, auxiliary springs mounted on the auxiliary frame between the main springs, and resilient connections between the upper ends of the auxiliary springs independent of the main base and upper rim frames and of the main springs. 75

6. In spring constructions, a marginal base frame, spiral marginal main springs secured at regular intervals on the sides and ends of the base frame, spacing rods secured to and supported by the marginal end main springs independently of the marginal base frame, spiral inner main springs secured at regular intervals on the spacing rods, an upper rim frame secured on the upper portions of the side and end main springs, intersecting strips interposed between the main springs over the spacing bars and secured at their ends to the base frame, and auxiliary springs each secured on the strips at their intersection with their upper ends independent of the main springs and the base and rim frames. 80

7. In spring constructions, a marginal base frame, spiral marginal main springs secured at intervals to the sides and ends of the base frame by their base convolutions, spacing rods secured to and supported by the base convolutions of the main springs independently of the base frame, an upper rim frame connecting the upper convolutions of the marginal main frames, spiral inner main springs each connected to and supported on the spacing rods by its lower convolution independently of the adjacent springs, the upper portion of said spring 100 being disconnected from the other springs and said frames, an auxiliary base frame consisting of crossed strips secured together at their intersections in spaced relation to clear the main springs and attached at their 105 ends to the marginal base frame, auxiliary springs of less height than the main springs each secured by its base convolution to a pair of auxiliary strips at the intersection thereof, and resilient bars connecting the 110 upper convolutions of the auxiliary springs, the spacing rods being adapted to bend under load on the main springs independently of the auxiliary strips, and the latter being adapted to flex only under load transmitted 115 by the auxiliary springs. 120

8. In spring constructions, a marginal base frame, spiral marginal main springs secured at intervals to the sides and ends of the base frame by their base convolutions, 125 spacing rods secured to and supported by the base convolutions of the main springs independently of the base frame, an upper rim frame connecting the upper convolutions of the marginal main frames, spiral 130

inner main springs each connected to and supported on the spacing rods by its lower convolution independently of the adjacent springs, the upper portion of said spring 5 being disconnected from the other springs and said frames, an auxiliary base frame consisting of crossed strips secured together at their intersections in spaced relation to clear the main springs and attached at their 10 ends to the marginal base frame, auxiliary springs of less height than the main springs each secured by its base convolution to a pair of auxiliary strips at the intersection thereof, and resilient bars connecting the 15 upper convolutions of the auxiliary springs,

the spring rods being adapted to bend under load on the main springs independently of the auxiliary strips, and the latter being adapted to flex only under load transmitted by the auxiliary springs, and the auxiliary 20 springs and supporting strips being removable without disturbance of the main springs and frames.

In testimony whereof I affix my signature in presence of two witnesses.
